UNITED STATES PATENT OFFICE.

WILLIAM J. MOXLEY, OF CHICAGO, ILLINOIS.

DESIGN FOR A BUTTER OR OLEOMARGARIN BRICK OR PRINT.

SPECIFICATION forming part of Design No. 32,784, dated June 5, 1900.

Application filed May 14, 1900. Serial No. 16,683. Term of patent 14 years.

To all whom it may concern:

Be it known that I, WILLIAM J. MOXLEY, a citizen of the United States, residing at Chicago, Illinois, have invented and produced a new and useful Design for Butter or Oleomargarin Bricks or Prints, of which the following is a specification.

In the drawings, Figure 1 represents a plan view of a butter-print, and Fig. 2 represents a longitudinal central elevation of the same.

As shown in the drawings, the leading or important feature of my design consists in a butter or oleomargarin brick or print having

on its upper or top surface a branch or spray of a rose-bush A in raised or relief work. 15 The branch of the rose-bush shows some buds and leaves and runs diagonally across the top surface of the brick or print.

What I regard as new, and desire to secure by Letters Patent, is— 20

The design for a butter or oleomargarin brick or print herein shown and described.

WILLIAM J. MOXLEY.
